UNITED STATES PATENT OFFICE.

FRED A. SAUNDERS, OF WINCHESTER, MASSACHUSETTS.

SASH-CORD HOLDER.

No. 918,772.

Specification of Letters Patent.

Patented April 20, 1909.

Application filed July 29, 1908. Serial No. 445,889.

To all whom it may concern:

Be it known that I, FRED A. SAUNDERS, of Winchester, in the county of Middlesex and State of Massachusetts, have invented certain new and useful Improvements in Sash-Cord Holders, of which the following is a specification.

This invention has for its object to provide improved means for coupling a sash cord to a window sash without the necessity of removing the sash from the window casing.

The invention consists in the improved device which I will now proceed to describe and claim.

Of the accompanying drawings, forming a part of this specification,—Figure 1 represents a perspective view of a sash cord holder embodying my invention. Fig. 2 represents a side elevation of the same, and an edge view of a portion of the sash to which the holder is secured. Fig. 3 represents a section on line 3—3 of Fig. 2. Fig. 4 represents a section on line 4—4 of Fig. 3. Fig. 5 represents a side view of the blank from which the holder is made.

The same reference characters indicate the same parts in all the figures.

In the drawings, 12 represents a portion of a window sash, said portion including parts of one of the vertical side bars, and one of the horizontal top bars.

13 represents the usual longitudinal groove which is formed in each of the vertical edges of the sash to receive the cord 14, the cord being shown in dotted lines in Figs. 2, 3, and 4.

The groove 13 is usually of substantially semi-circular form, as indicated in Fig. 4, and one end portion of the cord 14 is inserted in the groove and suitably secured therein; ordinarily, by providing the cord with a knot which engages an enlargement of the groove, this connection requiring the removal of the sash from the casing prior to the removal of a broken cord from the sash, and the application of another cord thereto.

My improved cord holder comprises an elongated sheet metal sheath 15 which is substantially semi-circular in cross section, and is adapted to enter the groove 13, and be interposed between the wall of the groove and the portion of the cord 14 which is within the groove. The sheath 15 is adapted to closely fit the cord, and is made of relatively thin sheet metal so that its interposition between the cord and the wall of the groove will not

cause the cord to project materially from the groove.

At the upper end of the sheath 15 is an attaching flange bent backwardly from the sheath at right angles thereto, and adapted to bear upon the upper end of the sash, as indicated in Fig. 3. Said flange is formed from the same piece of metal that constitutes the sheath. To compensate for the necessary thinness of the metal, the flange is formed by bending one end portion of the blank from which the holder is formed in such manner as to provide two flange layers or members 16 and 17, connected by a neck 18, which forms the outer end of the flange. The bending of the bottom layer 16 from the sheath forms a neck 19 connecting the sheath with the attaching flange. The blank from which the holder is made is of the general form represented in Fig. 5, in which the dotted line $z-z$ indicates the line on which the metal is bent to form the neck 19, while the line $y-y$ indicates the line on which the metal is bent to form the neck 18. One end of the blank is provided with an extension 20 which is bent downwardly along the line $z-z$ across the neck 19, so that the lip 20 bears upon the upper end of the sheath 15, and reinforces the neck 19 so that said neck is not liable to be bent or distorted by the upward strain exerted upon it by the weight attached to the sash cord. The flange formed as described is provided with screw holes 21 to receive the screws which attach the flange to the sash.

One end of the cord is attached to the sheath 15 by suitable means, such as a pin 22 passed through the cord and engaged with holes 23 formed for its reception in the sides of the sheath.

In case the sash cord becomes broken, the described holder may be removed from the sash after the withdrawal of the attaching screws. The end of the cord attached to the sheath may then be removed and another cord substituted for it, after which the sheath with the attached cord may be inserted in the groove 13, the sheath being moved endwise into the groove, and carrying with it the attached end of the cord until the attaching flange bears on the upper end of the sash. The holder may then be secured by re-inserting the attaching screws.

An important feature of my invention is the reinforced attaching flange made integral

with the sheath, and composed of two thicknesses, the top layer of the flange having the reinforcing lip 20 which strengthens the neck 19. As above stated, the metal of which the 5 sheath is made is necessarily relatively thin in order to prevent any material projection of the cord from the groove 13. The thinness of the metal is compensated for by the described construction of the attaching 10 flange with its lip 20, said construction giving the holder all the strength that is required, and preventing any tendency of the bending or distortion of the neck 19 by the upward strain exerted on it by the sash cord 13. 15 The sheath 15 is of practically uniform size from end to end so that all parts of it are adapted to enter the usual standard semi-circular groove 13 formed in the vertical edges of a sash. The holder is therefore 20 adapted to be applied to an old sash, no change in the form of the standard sash cord groove in the sash being required excepting possibly a slight enlargement of the upper end of the groove, to enable it to conform to 25 the slight spreading of the sides of the sheath at its upper end. This enlargement may be readily and quickly made by a jack knife.

It will be seen that the holder made as described from a single piece of thin sheet metal, is of very inexpensive construction, 30 and that its adaptability to be attached to a sash without material change in the form of the cord groove enables it to be quickly and cheaply applied.

I claim:—

A sash cord fastener comprising a sheet metal sheath formed to embrace a portion of a sash cord, and adapted to be moved end-wise in a sash cord groove, and an attaching flange integral with the sheath and formed by bending the sheet metal to form a two-layer flange, the inner layer of which is connected by a neck with the upper end of the sheath; the outer layer of the flange being bent backwardly upon the inner layer, and having a reinforcing lip which is bent over 40 said neck into the sheath.

In testimony whereof I have affixed my signature, in presence of two witnesses.

FRED A. SAUNDERS.
